CHLOROWAX-NAPHTHALENE CONDENSATION PRODUCT POUR DEPRESSANT FOR MIDDLE DISTILLATE FUELS

William E. Lifson, Union, and William C. Hollyday, Jr., Watchung, N.J., assignors to Esso Research and Engineering Company, a corporation of Delaware
No Drawing. Filed June 8, 1962, Ser. No. 200,919
3 Claims. (Cl. 44—62)

This invention relates to a product formed by condensing a particular kind of chlorinated wax with naphthalene in a prescribed Friedel-Crafts reaction to make the condensation polymer product a more potent pour depressant in petroleum middle distillate oils, such as heating oils and diesel fuels.

The middle distillate fuels are obtained as straight run and cracked petroleum oils which boil in the range of about 350° F. to 800° F. These oils are between kerosene and lubricating oils in volatility. A low pour point is required of any middle distillate fuel which is to be pumped or otherwise transferred at low temperatures. In general, pour points as measured by the well-known ASTM method have been found to be more reliable than filterability tests in indicating the minimum temperature at which these fuels can be used. In practical application, filters are (or can be) warmed soon after equipment start-up, and any wax crystals present in the fuel flowing to the filter melt and cause no trouble. However, if the pour point is too high and the fuel will not flow at the beginning, the equipment cannot be started.

It is also well known that the pour point is a good indication of the lowest operating temperature for a lubricating oil. Pour point depressants best adapted for lowering the pour points of lubricating oils have been made for many years by condensation of certain chlorinated waxes with naphthalene. The optimum composition of the reactants and the optimum reaction conditions have been discovered through research over a long period of time; but now, in accordance with the present invention, critical changes in the condensation product, particularly with respect to the kind of chlorinated wax reacted, have been discovered to make a product better adapted to and more potent for depressing the pour point of middle distillate fuels.

U.S. Patent 2,297,292 of G. H. B. Davis et al. describes the general method for making a pour point depressant effective for heavy oils, particularly lubricating oils, by Friedel-Crafts reaction of a chlorinated wax, preferably a high melting point wax (ca. 140° F. M.P.) chlorinated to contain preferably 10 to 15% chlorine.

The critical requirements which distinguish the synthesis and composition of the pour depressants which are effective in middle distillates, as made in accordance with the present invention, are:

(A) *Description of the wax.*—The paraffin wax should have a melting point in the range of 97° to 113° F., preferably 100° to 108° F., as determined by the ASTM method. This kind of wax is principally composed of normal paraffins which distill within the range of 370° to 470° F. under 10 mm. Hg absolute pressure.

(B) *Description of the chlorinated wax.*—The paraffin wax is chlorinated by known methods, but the chlorinated wax is made to contain 18 to 22 wt. percent chlorine.

(C) *Reactant ratio.*—In the Friedel-Crafts ($AlCl_3$ catalyzed reaction), 330 to 675 parts by weight (preferably 333 to 665 parts by weight) of the chlorinated wax are used per 100 parts by weight of the naphthalene to form the reaction mixture.

The criticality of these requirements were demonstrated

by many tests with control of the variables as shown in the following representative examples:

Example 1

5 Chemically pure normal eicosane ($n-C_{20}H_{42}$) with a melting point of 97° F. was chlorinated to 14 wt. percent chlorine by passing a stream of chlorine gas into the melted paraffin at 195° to 205° F.

This chlorinated paraffin (111 g.) was condensed with 10 13.1 g. of naphthalene in the Friedel-Crafts reaction to give 60 g. of polymeric product. The solvent was 44 ml. of o-dichlorobenzene, the catalyst was 2.5 g. of anhydrous aluminum chloride, the temperature was 100° to 120° F., and the time of reaction was about 5½ hours. Unreacted wax and chlorowax were extracted from the product with warm methanol (recovered 48 g.).

The pour depressant activity of this material in a typical middle distillate heating oil is shown in Table II.

Example 2

20 The n-eicosane was chlorinated as in Example 1, but to a higher chlorine content of 26 wt. percent.

Example 3

25 This is similar to Example 1 except a commercial highly n-paraffinic wax of 116° F. melting point was chlorinated to 14 wt. percent chlorine.

Preparative details of the Friedel-Crafts condensation product with naphthalene are given in Table I, and pour 30 depressant activity is illustrated in Table II.

Examples 4 and 5

35 These are similar to Example 1 except a commercial highly n-paraffinic wax of 123° F. melting point was chlorinated to 14 wt. percent and 18 wt. percent chlorine, respectively.

Preparative details of the Friedel-Crafts condensation product with naphthalene are given in Table I, and pour 40 depressant activity is illustrated in Table II.

Examples 6 to 13

(Examples according to this invention)

45 Preparative details of the Friedel-Crafts condensation products with naphthalene are given in Table III, and pour depressant activity is illustrated in Tables IV, V and VI.

In Examples 6 and 7, the n-eicosane described in Examples 1 and 2 was used. In Example 8, the wax was a commercial highly n-paraffinic wax of 100° F. melting point, 99% of which distilled in the range of 366° 50 to 425° F. and 90% in the range of 382° to 411° F.

The wax was chlorinated to 20 wt. percent chlorine and this chlorinated wax was condensed with naphthalene similar to Example 1.

In Examples 9 to 13, a n-paraffinic wax of 108° F. melting point was chlorinated to five different percentages of chlorine under the same conditions as for the n-eicosane in Example 1. Before chlorination, 99% of this wax distilled between 264° and 485° F. at 10 mm. Hg pressure and 90% distilled between 407° and 470° F. at that same 60 pressure.

TABLE I.—PREPARATION OF WAX/NAPHTHALENE

Example No.	M.P. of Wax, ° F.	Percent Cl in Cl Wax	G. Cl Wax/100 g. Naphthalene	G. Product/100 g. Naphthalene
1.-----	97	14	840	468
2.-----	97	26	405	412
3.-----	116	14	827	560
4.-----	123	14	827	584
5.-----	123	18	680	385

(None of these examples falls within the claims of this invention.)

TABLE II.—POUR DEPRESSANT ACTIVITY OF WAX/NAPHTHALENE¹

Wt. Percent Product	Pour Point, ° F., Using Product From—				
	Example 1	Example 2	Example 3	Example 4	Example 5

¹ In a cracked middle distillate of +20° F. pour point, +28° F. cloud point, 3.62 cs./100° F. viscosity, 22.5° API gravity, 408° to 660° F. distillation range, and 109° F. aniline point.

The observed data, as illustrated in the foregoing tables, has proved that there is a specific relationship between the kind of chlorinated wax condensed with a naphthalene and the effectiveness of the condensation product in a particular petroleum oil with respect to its boiling range. For effectiveness in the middle distillate oils which boil in the range of 350° F. to 800° F., the wax which is chlorinated should be principally straight chain or normal paraffinic wax having a melting point in the range of 97° F. to 113° F., preferably 100° F. to 108° F., and the chlorine content of such chlorinated wax should be in the range of 18 to 22 wt. percent, preferably from 19 to 21 wt. percent, with an optimum of 20 wt. percent. The ratio of the chlorinated wax reactant to the naphthalene is significant also in obtaining a most effective pour depressant for the middle distillate oils, which may be straight run petroleum fractions, cracked

petroleum fractions, or a mixture of straight run and cracked petroleum fractions boiling within the specified middle distillate oil boiling range. These pour point depressants are preferably to be added in a small proportion of about 0.01 to 0.20 wt. percent to the middle distillate fuels for imparting the desired improvement in lower pour point. Such fuels requiring improvement generally have a pour point above about -10° F. without the presence of a suitable pour point depressant. The four point depressants of the present invention are suitable for use in middle distillates having pour points between -10° F. and +30° F. and are particularly effective in middle distillates having pour points between 0° F. and +20° F.

The pour points were determined for three different middle distillates or gas oils in which the condensation products were added in concentrations of 0.01, 0.02, 0.03, 0.05 and 0.10% by weight. The total lowering of degrees F., obtained by adding the individual lowerings at each concentration, did not exceed 90 for Examples 1 to 5, whereas the totals for Example 11, the optimum according to the present invention, were 175, 115 and 140 in the three gas oils. Total lowerings of 115 minimum are generally characteristic of the performance of the pour point depressants of the products of the present invention.

The invention described is claimed as follows:

1. A composition of a middle distillate petroleum fuel oil blended with a small amount of about 0.01 to 0.2 wt. percent of a chlorinated wax-naphthalene condensation polymer for lowering its pour point, said middle distillate petroleum oil boiling in the range of 350° F. to 800° F., said condensation polymer being a product synthesized by reacting 100 parts by weight of naphthalene with 330 to 675 parts by weight of an n-paraffin wax containing 18 to 22 wt. percent chlorine in the presence of $AlCl_3$ catalyst, the said wax unchlorinated having an ASTM melting point of 97° F. to 113° F.

2. A composition of a middle distillate petroleum fuel oil blended with a small amount of about 0.01 to 0.2 wt. percent of a chlorinated wax-naphthalene condensation

polymer for lowering its pour point, said middle distillate petroleum oil boiling in the range of 350° to 800° F., said condensation polymer being a product synthesized by reacting 100 parts by weight of naphthalene with 330 to 675 parts by weight of an n-paraffin wax containing 19 to 21 wt. percent chlorine in the presence of AlCl_3 catalyst, the said wax unchlorinated having an ASTM melting point of 100° to 113° F.

3. A wax-naphthalene condensation polymer of increased effectiveness as a pour depressant in a middle distillate petroleum fuel oil, said polymer consisting essentially of the condensation reaction product synthesized by reacting 100 parts by weight of naphthalene with 330 to 675 parts by weight of a chlorinated n-paraffin wax containing 18 to 22 wt. percent of chlorine in the presence of

aluminum chloride as catalyst, said wax unchlorinated having an ASTM melting point of 97° F. to 113° F.
